SHOE SUPPORT

Fred E. Hooper, Swampscott, Mass., assignor to
 United Shoe Machinery Corporation, Paterson,
 N. J., a corporation of New Jersey

Application February 12, 1932, Serial No. 592,600

27 Claims. (Cl. 12—126)

This invention relates to means for supporting shoes and the lasts on which they are mounted (the term "shoe" being generally used herein after as inclusive of the last), and has more particular reference to means for supporting a shoe forwardly of its heel-end portion against pressure applied on its bottom face. The invention is herein illustrated as embodied in supporting means designed for use in a bed-lasting machine, but it is to be understood that it is not thus limited in its applicability.

An object of the invention is to provide improved supporting means so constructed as to afford a firm support for each shoe without danger of excessive pressure on any portion of the upper materials. To this and other ends, in accordance with one feature of the invention, the supporting means herein shown comprises a novel arrangement of supporting members that are relatively movable to conform substantially to the contour of each shoe so that the pressure on the shoe is distributed with substantial uniformity over a considerable area. In the construction illustrated there are provided different sets of members for supporting respectively the opposite side portions of the shoe, i. e., portions at opposite sides of a median plane extending heightwise and lengthwise of the shoe, the members of each set being arranged in contiguous relation to one another in a series extending lengthwise of the shoe and being mounted for turning movements relatively to one another about an axis also extending lengthwise of the shoe to conform substantially to the contour of the shoe. As herein shown each set comprises three such members, although it is to be understood that the invention is not limited to that particular number. It is a further object of the invention, in the manufacture of some kinds of shoes provided with toe tips, to avoid pressure on the upper forwardly of the tip line, where excessive pressure might cause the box toe solvent to penetrate to the outer surface of the upper, and accordingly, as illustrated, the construction and arrangement are such that the supporting pressure is applied to the shoe mainly along its instep portion.

In accordance with further features of the invention provision is afforded for various movements of the supporting means for still better conformity to the shape and position of each shoe, the construction shown being such that the above-mentioned sets of supporting members are movable as a unit about axes extending widthwise, heightwise and lengthwise of the

shoe. More particularly, as illustrated, the sets of members are supported on a holder which can tip against yielding resistance about an axis extending widthwise of the shoe in response to pressure of the shoe on the members, the holder being mounted on a stem that can turn against yielding resistance about an axis extending heightwise of the shoe, and the stem is mounted in a post that can swing to a limited extent about an axis extending lengthwise of the shoe. 10 It is to be understood that in the provision thus afforded for different movements of the supporting means the invention, in some of its novel aspects, is not limited to a shoe rest having different sets of supporting members constructed and arranged as hereinabove described. 15

The above and other features of the invention, including various novel details of construction and combinations of parts, will now be more particularly described by reference to the accompanying drawing and pointed out in the claims. 20

In the drawing,

Fig. 1 is a view mainly in side elevation of shoe-supporting means constructed in accordance with this invention, together with other portions of a bed-lasting machine to which this means is applied; 25

Fig. 2 shows the shoe-supporting means in elevation as viewed from the right in Fig. 1; and Fig. 3 is a section on the line III—III of Fig. 1. 30

The invention is illustrated as applied to a bed-lasting machine of a well-known type, characteristic features of which are disclosed in Letters Patent No. 1,018,477, granted on February 27, 1912 upon an application of Matthias Brock. 35 Such a machine includes in its organization a heel post 10 on which is mounted a spindle 12 for engaging the heel end of the last in its spindle hole, and toe-embracing wipers 14 for wiping the toe-end portion of the upper into lasted position. The wipers are supported on a toe head, not shown in detail, by which they are moved upwardly and downwardly in operating on the shoe, the toe head being also adjustable lengthwise of the shoe. A machine of this type further includes a device, commonly known heretofore as a toe rest, for supporting the shoe forwardly of its heel-end portion against pressure applied on its bottom face, this device being movable upwardly to jack the shoe in the operation of the 45 machine by a bracket 16 that controls it. 50

For purposes of this invention there is herein disclosed novel means for supporting the shoe forwardly of its heel-end portion, the construction shown comprising two sets of members or 55

blocks 18, 20 and 22 arranged to support respectively the opposite side portions of the shoe. The blocks of each set are arranged in contiguous relation to one another in a series extending lengthwise of the shoe and are supported on a pin 24 for turning or tipping movements relatively to one another about a common axis also extending lengthwise of the shoe. Each pin 24 is mounted for turning movement in lugs 26 and 28 of a holder 30 supported as hereinafter described, and each end block 18 is secured on its supporting pin 24 at one side of the lug 26 by a small pin 32 shown in dotted lines in Fig. 1. The two blocks 20 and 22 of each set are mounted to turn on the pin 24 between the lugs 26 and 28 by which they are confined against movement lengthwise of the pin, each block 20 being so formed that a portion thereof extends over the lug 26 so as to contact with the end block 18. It will be understood that each pin 24 is held against lengthwise movements in its bearings in the lugs 26 and 28 by the block 18 fast on one end of the pin and by a head on the other end of the pin in engagement with the lug 28. Each of the blocks 18, 20, 22 is shaped to present a supporting face that is somewhat concave laterally of the shoe, and the arrangement of the two sets of blocks is such as to present a hollow to receive the shoe, the supporting faces of the blocks extending laterally of the shoe in locations opposite the top of the shoe. Over each set of blocks is a pad 34, which may be made of felt and is preferably secured in any suitable manner, as by a screw, to the middle block 20; and over both the pads 34 is a cover 36, preferably of leather, fastened to each block 20 by a screw 38. The cover 36 is slit at its corners to permit its end portions to be readily turned downward, and these end portions are secured to the side portions of the cover by wire hooks 40. The cover thus mounted tends to retain the several blocks approximately in the relations to one another that they assume in operating on a shoe, while permitting them readily to turn relatively to one another in response to pressure of each shoe thereon so as to conform substantially to the contours of shoes of different sizes and shapes.

In the manufacture of some kinds of shoes that are provided with toe tips it is desirable to avoid any considerable pressure on the top of the forepart of the upper forwardly of the tip line in the lasting operation because of the danger that the box toe solvent may penetrate to the outer surface of the upper. Accordingly the construction herein shown is such that the supporting means or shoe rest above described applies its pressure to the shoe at the rear of the tip line and mainly, as illustrated, along the instep portion of the shoe, the term "shoe" being commonly used herein; as above explained, to include the last. As shown in Fig. 1 the two sets of supporting members 18, 20, 22 with the pins 24 are inclined lengthwise of the shoe, when in operative positions, similarly to the instep portion of the shoe. In order that the supporting means may readily conform in this respect to shoes of different sizes and shapes, the holder 30 is pivotally mounted on a pin 42 extending laterally of the shoe and supported on the head 44 of a stem 46 which is mounted in a post 48. A screw 50 in the head 44 is arranged to contact with the holder 30 to act as a stop for determining the initial position of the holder with respect to movement about the axis of the pin 42, and springs 52 connected to the holder and to the base of the post 48 tend to maintain the holder in the position deter-

mined by the screw, the latter being adjustable to vary that position. It is contemplated that preferably the screw 50 will be so adjusted that initially the two sets of supporting members will extend lengthwise of the shoe in directions somewhat more nearly horizontal than the slope of the instep, so that portions of the sets of members that are farthest from the toe end of the shoe will press initially on the shoe, as a result of which the sets of members will be tipped into substantially parallel relation to the lengthwise inclination of the instep by pressure of the shoe thereon at one side of the axis of the pin 42, as illustrated in Fig. 1. It will be understood that the springs 52 are comparatively light springs and do not oppose any great resistance to such tipping of the holder 30 under control of the shoe.

The stem 46 is vertically movable in the post 48 and carries at its lower end a screw 54 the head of which is arranged to rest on the post at the lower end of the recess in which the stem is mounted, the screw being adjustable to vary the height of the stem and the parts supported thereon. It will be evident that the springs 52 serve additionally to hold the stem 46 down in the position determined by the screw 54. The stem 46 may also turn in the post 48 about an axis extending heightwise of the shoe to permit the supporting members 18, 20, 22 to adjust themselves still more readily to different shoes, including right shoes and left shoes. A leaf spring 56 fastened to the head 44 of the stem 46 and bearing on a flattened face 58 on the post 48 tends to maintain the stem 46 and the parts supported thereon in a central position while permitting such turning movements as may be required by differences in the contours or positions of different shoes. For still better accommodation to different shoes, the post 48 is pivotally mounted on a pin 60 to swing or tip laterally of the shoe about an axis extending lengthwise of the shoe, the pin being supported in lugs on a block 62 which is adjustably mounted on a plate 64 fast on the bracket 16. The post is thus free to swing, but only to a limited extent, its movements in opposite directions being limited by shoulders 66 at its lower end in engagement with faces 68 on the block 62. The plate 64 is so formed as to provide a guideway along which the block 62 is adjustably movable lengthwise of the shoe. To maintain the block 62 in adjusted position there is provided a pawl 70 fast on a rod 72 which is mounted to turn in bearings in the block, the pawl being arranged to engage ratchet teeth 74 on the plate 64. A spring 76 in the block 62 presses the pawl against the ratchet teeth, and for lifting it from the teeth when it is desired to move the shoe-supporting means forwardly there is provided a handle 78 fast on the rod 72. It will thus be seen that the means for supporting the forepart of the shoe is adjustable lengthwise of the shoe independently of the toe head previously referred to as adjustable in that manner in bed-lasting machines of the illustrated type.

From the foregoing description it will be evident that there is provided by this invention shoe-supporting means so constructed as to adjust itself readily in accordance with the shape and position of each shoe and to conform substantially to the contour of that portion of the shoe where the supporting pressure is applied, so as to afford a firm support without excessive pressure in any location, the illustrated construction being further such that the shoe is supported by

engagement therewith rearwardly of the tip line for the purpose hereinbefore explained.

Having described the invention, what I claim as new and desire to secure by Letters Patent of the United States is:

1. A device for supporting a shoe forwardly of its heel-end portion against pressure applied on its bottom face, said device comprising different sets of members arranged to support respectively the opposite side portions of the shoe against pressure applied on the shoe bottom, the members of each set being arranged in substantially contiguous relation to one another in a series extending lengthwise of the shoe and being mounted for relative turning movements to conform substantially to the contour of the shoe.
2. A device for supporting a shoe forwardly of its heel-end portion against pressure applied on its bottom face, said device comprising different sets of members arranged to support respectively the opposite side portions of the shoe against pressure applied on the shoe bottom, the members of each set being arranged in a series extending lengthwise of the shoe and being mounted for relative turning movements about a common axis to conform substantially to the contour of the shoe.
3. A device for supporting a shoe forwardly of its heel-end portion against pressure applied on its bottom face, said device comprising different sets of members for supporting respectively the opposite side portions of the shoe, the members of each set being arranged in substantially contiguous relation to one another in a series extending lengthwise of the shoe with their shoe-supporting faces extending laterally of the shoe and being mounted for turning movements relatively to one another and relatively to the members of the other set about an axis extending lengthwise of the shoe to conform substantially to the contour of the shoe.
4. A device for supporting a shoe forwardly of its heel-end portion against pressure applied on its bottom face, said device comprising different sets of members for supporting respectively the opposite side portions of the shoe, the members of each set being arranged to press on the shoe respectively in different locations along the top of the shoe, and means supporting said members for turning movements, each about a predetermined axis, in response to pressure of the shoe thereon to permit them to assume relative positions in substantial conformity to the contour of the shoe.
5. A device for supporting a shoe forwardly of its heel-end portion against pressure applied on its bottom face, said device comprising different sets of members for supporting respectively the opposite side portions of the shoe, the members of each set being arranged in substantially contiguous relation to one another to press on the shoe over a substantially continuous area extending laterally of the shoe and being mounted for relative turning movements in response to pressure of the shoe thereon to permit them to assume relative positions in substantial conformity to the contour of the shoe.
6. A device for supporting a shoe forwardly of its heel-end portion against pressure applied on its bottom face, said device comprising two sets of blocks arranged to support respectively the opposite side portions of the shoe against pressure applied on the shoe bottom, the blocks of each set being arranged in a series extending lengthwise of the shoe and being mounted

turning movements about an axis extending lengthwise of the shoe to permit them to adjust themselves in substantial conformity to the contour of the shoe, and a flexible cover for transmitting the pressure of the blocks to the shoe.

7. A device for supporting a shoe forwardly of its heel-end portion against pressure applied on its bottom face, said device comprising different sets of members arranged to support respectively the opposite side portions of the shoe against pressure applied on the shoe bottom, the members of each set being arranged in a series extending lengthwise of the shoe and being mounted for relative turning movements to conform substantially to the contour of the shoe, a pad of yieldable material mounted on each set of members, and a flexible cover extending over both pads for engagement with the shoe.

8. A device for supporting a shoe at its instep portion against pressure applied on its bottom face, said device comprising different sets of members for supporting the shoe respectively at the opposite sides of its instep portion, the members of each set being arranged in a series extending lengthwise of the instep and being relatively movable laterally of the shoe to permit them to adjust themselves in substantial conformity to the contour of the shoe.

9. A device for supporting a shoe at its instep portion against pressure applied on its bottom face, said device comprising different sets of members arranged respectively to support the shoe at the opposite sides of the instep, the members of each set being arranged in a series extending lengthwise of the shoe and being mounted for relative turning movements about an axis inclined similarly to the instep portion of the shoe to permit them to adjust themselves in substantial conformity to the contour of the shoe.

10. A device for supporting a shoe at its instep portion against pressure applied on its bottom face, said device comprising two sets of blocks arranged to present a hollow to receive the shoe and to support the shoe respectively at the opposite sides of its instep portion, the blocks of each set being arranged in a series extending in a direction lengthwise of the instep and being movable relatively to one another, each about an axis extending also in that general direction, to permit them to adjust themselves in substantial conformity to the contour of the shoe.

11. A device for supporting a shoe forwardly of its heel-end portion against pressure applied on its bottom face, said device comprising different sets of members for supporting respectively the opposite side portions of the shoe, the members of each set being relatively movable to conform substantially to the contour of the shoe, and a holder supporting said different sets of members and mounted for movement about an axis extending laterally of the shoe.

12. A device for supporting a shoe forwardly of its heel-end portion against pressure applied on its bottom face, said device comprising different sets of members for supporting respectively the opposite side portions of the shoe, the members of each set being relatively movable to conform substantially to the contour of the shoe, a holder supporting said different sets of members and mounted to tip about an axis extending laterally of the shoe, and spring means controlling said holder and against the resistance of which it is movable about said axis in response to pressure of the shoe on the supporting members.

13. A device for supporting a shoe forwardly

- of its heel-end portion against pressure applied on its bottom face, said device comprising different sets of members for supporting respectively the opposite side portions of the shoe, the members of each set being relatively movable to conform substantially to the contour of the shoe, a holder supporting said different sets of members and mounted for movement about an axis extending laterally of the shoe, a spring tending to move said holder in one direction about its axis, and adjustable means arranged to act in opposition to said spring to determine variably the position of said holder.
14. A device for supporting a shoe forwardly of its heel-end portion against pressure applied on its bottom face, said device comprising different members arranged to support respectively the opposite side portions of the shoe and relatively movable to conform substantially to the contour of the shoe, and means supporting said relatively movable members for movement as a unit about an axis extending laterally of the shoe in response to pressure of the shoe thereon.
15. A device for supporting a shoe at its instep portion against pressure applied on its bottom face, said device comprising different sets of members arranged respectively to support the shoe at the opposite sides of the instep, the members of each set being relatively movable to conform substantially to the contour of the shoe, a holder supporting said different sets of members and mounted for movement about an axis extending laterally of the shoe, and yieldable means for maintaining said holder in position for portions of the sets of members that are farthest from the toe end of the shoe to press initially on the shoe, the holder being movable about its axis against the resistance of said yieldable means in response to pressure of the shoe on the members to incline the sets of members similarly to the lengthwise slope of the instep.
16. A device for supporting a shoe at its instep portion against pressure applied on its bottom face, said device comprising a shoe rest mounted for movement about an axis extending laterally of the shoe and having members relatively movable to conform substantially to the contour of the instep portion of the shoe, and spring means for maintaining said shoe rest in position for the portion thereof that is farthest from the toe end of the shoe to press initially on the shoe, the shoe rest being movable about its axis against the resistance of said spring means to a position inclined similarly to the slope of the instep in response to the pressure of the shoe thereon.
17. A device for supporting a shoe forwardly of its heel-end portion against pressure applied on its bottom face, said device comprising a shoe rest arranged to act on the shoe forwardly of its heel-end portion and mounted for movement about an axis extending laterally of the shoe, a spring tending to move said shoe rest in one direction about its axis, and a stop cooperating with said spring to determine the normal position of the shoe rest and adjustable to vary that position.
18. A device for supporting a shoe forwardly of its heel-end portion against pressure applied on its bottom face, said device comprising a shoe rest arranged to act on the shoe forwardly of its heel-end portion, a stem supporting said shoe rest and mounted to turn about an axis extending heightwise of the shoe, a post in which said stem is mounted, and a leaf spring fastened to said stem and arranged to act on said post to maintain the stem and the shoe rest normally in a centralized position, the shoe rest and stem being movable about said axis against the resistance of the spring to conform substantially to the contours of different shoes.
19. A device for supporting a shoe at its instep portion against pressure applied on its bottom face, said device comprising a shoe rest having different portions arranged to support the shoe respectively at the opposite sides of the instep, the shoe rest being movable about an axis extending heightwise of the shoe to conform substantially to the contours of different shoes, and spring means arranged normally to centralize the shoe rest with respect to movement about said axis but yieldable to permit such movement.
20. A device for supporting a shoe forwardly of its heel-end portion against pressure applied on its bottom face, said device comprising a shoe rest arranged to act on the shoe forwardly of its heel-end portion, and a post supporting said shoe rest and so mounted as to permit it to swing relatively to the shoe in one direction or the other laterally of the shoe about an axis extending lengthwise of the shoe in response to pressure of the shoe on the shoe rest.
21. A device for supporting a shoe forwardly of its heel-end portion against pressure applied on its bottom face, said device comprising a shoe rest arranged to act on the shoe forwardly of its heel-end portion, a post supporting said shoe rest and free to swing in one direction or the other about an axis extending lengthwise of the shoe in response to the action of the shoe on the shoe rest, and a support for said post having means for limiting its swinging movements when there is no shoe in engagement with the shoe rest.
22. A device for supporting a shoe forwardly of its heel-end portion against pressure applied on its bottom face, said device comprising a shoe rest arranged to act on the shoe forwardly of its heel-end portion and mounted for tipping movement about an axis extending widthwise of the shoe, and a member on which the shoe rest is thus mounted, said member being movable about an axis extending heightwise of the shoe for positioning the shoe rest differently in accordance with the contours of different shoes.
23. A device for supporting a shoe forwardly of its heel-end portion against pressure applied on its bottom face, said device comprising a shoe rest arranged to act on the shoe forwardly of its heel-end portion and so mounted as to permit it to adjust itself to the shoe about an axis extending widthwise of the shoe, and a member supporting said shoe rest and so mounted as to permit the shoe rest also to adjust itself to the shoe about an axis extending heightwise of the shoe.
24. A device for supporting a shoe forwardly of its heel-end portion against pressure applied on its bottom face, said device comprising a shoe rest arranged to act on the opposite side portions of the shoe forwardly of its heel-end portion and mounted for movement about an axis extending widthwise of the shoe, a stem on which the shoe rest is thus mounted, said stem being movable about an axis extending heightwise of the shoe, and a post supporting said stem and mounted for movement about an axis extending lengthwise of the shoe.
25. A device for supporting a shoe forwardly of its heel-end portion against pressure applied on its bottom face, said device comprising a shoe

rest arranged to act on the opposite side portions of the shoe forwardly of its heel-end portion, a member supporting said shoe rest and movable about an axis extending heightwise of the shoe, 5 and a support for said member movable about an axis extending lengthwise of the shoe.

26. A device for supporting a shoe forwardly of its heel-end portion against pressure applied on its bottom face, said device comprising a shoe 10 rest arranged to act on the opposite side portions of the shoe forwardly of its heel-end portion, and means for supporting said shoe rest so constructed as to permit the shoe rest to adjust itself to

the shoe about each of two axes extending respectively heightwise and lengthwise of the shoe.

27. A device for supporting a shoe forwardly of its heel-end portion against pressure applied on its bottom face, said device comprising a shoe 5 rest arranged to act on the opposite side portions of the shoe forwardly of its heel-end portion, and means for supporting said shoe rest so constructed as to permit the shoe rest to adjust itself to the shoe about axes extending respectively widthwise, 10 heightwise and lengthwise of the shoe.

FRED E. HOOPER.
